UNITED STATES PATENT OFFICE.

THOMAS H. POWERS, OF TEMPLEMAN CROSS ROADS, VIRGINIA, ASSIGNOR OF ONE-HALF TO ROBERT L. PARKER, OF TEMPLEMAN CROSS ROADS, VIRGINIA.

TOMATO-SCALDER.

1,112,552.

Specification of Letters Patent.

Patented Oct. 6, 1914.

Application filed January 7, 1914. Serial No. 810,889.

To all whom it may concern:

Be it known that I, THOMAS H. POWERS, a citizen of the United States of America, residing at Templeman Cross Roads, in the 5 county of Westmoreland and State of Virginia, have invented certain new and useful Improvements in Tomato-Scalders, of which the following is a specification.

This invention relates to improvements in 10 tomato scalders such as are used in canning factories for the purpose of partially cooking the tomatoes and of thoroughly cleansing the same.

The objects of the invention briefly stated 15 are to provide a tomato scalding tank which may be readily and quickly cleaned; in which provision is made for the efficient precipitation and removal of foreign matter or "sludge"; in which the operation of the 20 machine will not be substantially interrupted should it become necessary to clean the scalding tank while the machine is in use; in which any accumulation of sludge is not particularly liable to contaminate the tomatoes; which may be readily operated by 25 manual power and by a single attendant; and which is capable of substantially continuous use in scalding and cleaning the tomatoes and, therefore, has a relatively large 30 output.

An embodiment of the invention is illustrated in the accompanying drawings, wherein:—

Figure 1 is a perspective view of a machine in which the features of the invention are incorporated; Fig. 2 is a longitudinal sectional view in a median plane through one of the scalding tanks; Fig. 3 is a cross sectional view of the machine; and Fig. 4 is 40 a detail fragmentary view of the bottom of one of the scalding tanks.

Similar characters of reference designate corresponding parts throughout the several views.

45 The machine shown in the accompanying drawings includes two scalding tanks 1 and these tanks and their appurtenances are similar in construction. A description of one will, therefore, suffice for both.

50 Each tank 1 is of rectangular outline and has a specially constructed bottom 2, the essential characteristic of which is that it is of convex form and is provided at its ends with openings 3 through which the precipitated sludge is discharged, the openings 3

lining with connections in which are arranged the gates for regulating the discharge of the sludge. As these connections and gates, *per se*, form no part of the invention, their illustration is not deemed necessary. The bottom 2 is symmetrical in outline and has such longitudinal curvature that relatively steep downwardly inclined surfaces 6 are provided at each side of its transverse center along which the precipitated sludge readily flows in its passage to the discharge openings 3. The inclined surfaces 6 of the bottom 2 in combination with the perpendicular end walls 7 of the tank 1 define pockets 8 disposed transversely of the tank and at each side of the transverse center thereof of gradually tapering outline; and the openings 3 are arranged at the lowest and narrowest end of these pockets. The path along which the sludge flows in its passages over the surfaces 6 is also of tapering outline, being narrowest at its lowest end and having a minimum width which is substantially equal to the diameter of the openings. For this purpose baffles or 50 guides 9 are arranged at each side of the pockets 8, these baffles adjoining the side walls of the tank and having their edges, whereat they join the surfaces 6 inclined oppositely to one another to define the tapering flow-way for the precipitated sludge. The baffles or guides 9 are preferably convexly curved in cross section, thus having the substantial form of a quarter segment of a cone, for the purpose of readily deflecting 55 precipitated foreign matter upon the surfaces 6.

The tank 1 is partially filled with water in any suitable manner and the water level is determined by the elevation of an escape 60 pipe 10 which may be conveniently located in one of the end walls 7. The water in the tank is heated by steam and for this purpose steam pipes 11 are arranged within the tank adjacent and parallel to the side walls 100 thereof. The pipes 11 are provided with closely associated discharge openings 12 through which the steam is delivered in the form of fine jets of considerable strength into the water in the tank. The openings 12 are arranged at or near the undersides of the pipes 11 in order that the steam jets may be directed downwardly and hence may promote the settling of precipitated foreign matter upon the bottom 2. The pipes 110

11 extend from end to end of the tank and are arranged in close relation to the highest part of the bottom 2. Preferably the pipes 11 rest on said bottom and on the baffles 9 5 and receive substantial support from these elements.

The tomatoes to be scalded are arranged in the foraminous baskets usual for the purpose and these baskets are placed upon a 10 platform 13 which is of rectangular outline and is lowered into the tank to submerge the tomatoes in the water and raised from the tank to permit the removal of the baskets when the scalding operation has been completed. The platform 13 is of suitable 15 skeleton construction, preferably consisting of an angle iron frame 14 having its end bars connected by longitudinal slats 15. In its lowermost position the platform 13 comes 20 to rest in close proximity to the pipes 11 and preferably directly upon said pipes.

Where the tanks are employed in duplicate as shown and preferred, special operating mechanism is provided for the platforms 13, the arrangement being such that 25 these platforms work in alternation, that is to say, when one platform is lowered the other is raised and vice versa. This platform operating mechanism may be conveniently actuated manually by a single attendant 30 and consists of a longitudinal rock shaft 16 supported above the tanks in line with the median dividing wall thereof and journaled in uprights 17 secured to the end wall 35 of the apparatus; cross arms 18 secured at their centers upon the shaft 16; links 19 connecting the ends of the arms 18 and the platforms 13, the links being secured to the centers of hangers 20 co-planar with the end 40 bars of the frame 14; a two armed operating lever 21 secured at its center to one of the uprights 17; a cross arm 22 secured at its center upon a projecting end of the shaft 16 and links 23 connecting the ends of the 45 arm 22 and the lever 21. The links 19 are detachably connected to the hangers 20, the pivots being mounted upon pivoted spring pressed levers 24, which may be operated to disconnect said links and thus permit of the 50 complete removal of the platform from the tank. The platforms are removed when in elevated position and consequently the removal of a platform does not interfere with the scalding operation taking place in the 55 adjoining tank. The removal of each platform enables easy access to the interior of the tank for the purposes of cleaning, adjustment or repair, since when the platform is removed, the whole interior of the tank 60 is accessibly exposed.

The construction of the bottom 2 as above described is of advantage in that two relatively small streams of sludge, neither of which is liable to choke or clog the sludge 65 outlet are produced, instead of one large

stream as heretofore. It is important that foreign matter should be thoroughly precipitated and quickly removed, in order to prevent the steam jet openings from becoming clogged with consequent liability of contamination of the tomatoes. The production of two relatively small streams of sludge, as above stated, insures the ready discharge of the sludge through the sludge gates; the form of the bottom 2 insures the 70 ready passage of the sludge to the outlets; and the arrangement of the steam pipes in close proximity to the bottom and to the platform (when lowered) with the jets of said pipe opening downwardly, insures the 75 ready precipitation of the sludge upon the bottom 2. Even though one of the sludge gates should by chance become clogged, at least half of the sludge discharges through the other gate and consequently it is practical 80 to clean the clogged sludge gate without substantial interference with the operation of the machine. A further important advantage which is secured by the provision of the arched bottom 2, in combination with 85 the steam pipes delivering downwardly directed jets of steam, is that any foreign matter which may be in suspension in the water will always be kept at a stratum or level substantially below the tomatoes being 90 scalded and consequently the rapidity and thoroughness of the cleaning operation is greatly promoted. In other words, precipitated foreign matter is effectually prevented from circulating, before it settles 95 upon the bottom 2, through the immediate stratum of water in which the tomatoes are submerged.

When using two platforms working in alternation, the scalded tomatoes may be removed from and fresh tomatoes may be placed upon the elevated platform simultaneously with the scalding operation in the other tank in which the loaded platform is in lowermost position.

As a matter of convenience, pivoted supports 25 may be provided to engage either of the elevated ends of the lever 23 and positively hold the platforms against movement during the scalding operation in which either of the platforms may be utilized.

Having fully described my invention, I claim:

1. A tomato scalding comprising a tank having a bottom oppositely inclined from a central elevated point and provided with sludge outlets at its lowest points adjoining the ends of the tank, steam pipes arranged within the tank close to said bottom and having steam discharge openings, and a tomato carrier movable in the tank above said steam pipes.

2. A tomato scalding comprising a tank having a bottom oppositely inclined from a central elevated point and provided with

sludge outlets at its lowest points adjoining the ends of the tank, baffles arranged at the sides of the tank and defining flow-ways for the solid matter which is precipitated upon 5 said bottom, said flow-ways tapering toward said outlets, steam pipes arranged within the tank close to said bottom and having steam discharge openings, and a tomato carrier movable in the tank above said steam

10 pipes.

3. A tomato scalder comprising a tank having a bottom oppositely inclined from a central elevated point provided with sludge

outlets at its lowest ends adjoining the ends of the tank, steam pipes arranged within the 15 tank close to said bottom, the steam pipes having downwardly directed steam discharge openings, and a tomato carrier movable in said tank above said steam pipes.

In testimony whereof I have hereunto set 20 my hand in presence of two subscribing witnesses.

THOMAS H. POWERS.
